UNITED STATES PATENT OFFICE.

PAUL L. CROWE, OF JERSEY CITY, NEW JERSEY.

STOKER.

1,077,872.

Specification of Letters Patent.

Patented Nov. 4, 1913.

Application filed October 1, 1907. Serial No. 395,466.

To all whom it may concern:

Be it known that I, PAUL L. CROWE, a citizen of the United States, residing at Jersey City, in the county of Hudson and State of New Jersey, have invented certain new and useful Improvements in Stokers; and I do hereby declare the following to be a full, clear, and exact description of the invention, such as will enable others skilled in the art to which it appertains to make and use the same.

This invention relates to stokers, and has for an object to provide a stoker embodying new and improved features of underfeeding.

A further object of the invention is to provide in a stoker improved means for forcing fuel downwardly at an incline below the ignition surface of the fuel contained in the combustion chamber.

A further object of the invention is to provide in a stoker improved means for conducting air from a conduit or air chamber into the burning mass.

A further object of the invention is to provide in a stoker an inclined fuel supporting surface with an improved ash dumping grate or plate disposed at the lower end of the incline.

A further object of the invention is to provide in a stoker an inclined fuel supporting surface with improved means for agitating the fuel mass and forcing fresh fuel under the burning mass.

A further object of the invention is to provide in a stoker an improved twyer block adapted for association with the form of retort or fuel supporting trough disclosed herein, or in association with other retorts.

With these and other objects in view, the invention consists of certain novel constructions, combinations and arrangements of parts, as will be hereinafter fully described and claimed.

In the drawings:—Figure 1 is a vertical sectional view of the improved stoker in association with a conventional combustion chamber and boiler. Fig. 2 is an inverted plan view of the stoker mechanism as seen along arrow 2 of Fig. 1. Fig. 3 is a top plan view of one section of the improved stoker mechanism with the twyer blocks as seen along arrow 3 of Fig. 1. Fig. 4 is a transverse sectional view through two of the fuel troughs as on line 4—4 of Fig. 1. Fig. 5 is a longitudinal sectional view of one of the fuel troughs as on line

5—5 of Fig. 4. Fig. 6 is a perspective view of one of the twyer blocks. Fig. 7 is a perspective view of a plate adapted for use at the lower end of a fuel trough and to support the extreme twyer block. Fig. 8 is a view in end elevation of the lower extremity of the fuel trough showing the means for maintaining the shafts in association therewith. Fig. 9 is a view in rear elevation of a means for mounting the ash plate or grate. Fig. 10 is a view of the ash plate or grate in end elevation. Fig. 11 is a diagrammatic view of the blower associated with the stoker mechanism.

Like characters of reference designate corresponding parts throughout the several views.

The stoker forming the subject-matter of this application is adapted for association with a furnace for any approved use and represented conventionally by a rear wall 15 and a front wall or arch 16, with a conventional water tube boiler 17 mounted above the arch. It is also, of course, to be understood that side walls 18 are provided, thereby limiting and defining the size and position of the stoker.

The stoker comprises a plurality of fuel troughs 19 disposed at an inclination with the higher ends toward the outer end of the furnace or combustion chamber and shown under the conventional arch 16. The troughs are supported in any approved manner, as by an angle iron 20 secured to the under side of the front arch and any approved number of fuel troughs may be employed by providing the said troughs with flanges 21, along their lower or under sides and bolting the several sections together by means of bolts, as 22, through the flanges.

The fuel troughs 19 are located as shown with reference to flanged under plates 23, defining between the said under plate 23 and the bottom of the fuel trough 19 a space, as 24, through which air is supplied to the stoker in any approved manner, as through the opening 25, but the invention is not limited to the integrality above referred to.

Along the greater portion of their lengths the fuel troughs 19 are spaced apart at their upper longitudinal edges as shown particularly at 26 in Figs. 3 and 4, and a plurality of twyer blocks 27 are disposed between the said spaced longitudinal edges. The twyer blocks, as shown particularly in Fig. 6, comprise a central or body portion having flanges 28 formed at their upper edges, pref-

erably disposed at an angle to each other to form with the base of the twyer block approximately a triangle. The base of the twyer block is provided with notches forming shoulders 29 spaced at a little distance below the lower extremities of the flanges 28 so that when the twyer blocks bear upon the longitudinal edges of the fuel troughs a plurality of openings are provided, as 5 indicated at 30 above the edge of the trough and beneath the extremities of the flanges 28. It will thus be seen that when air is forced into the chamber 24, it is allowed to pass outwardly in a large number of jets through 10 the openings formed as above described and into the fuel mass which is disposed upon the inclined supporting surface. To further assist in properly spacing the twyer blocks, a rib 31 may be employed disposed to engage 15 a similar rib carried upon the adjacent block to space the blocks apart centrally, the said twyer blocks being maintained in operative positions by the edges of the fuel troughs engaging the dove-tailed lower portions. 20

Within the fuel troughs 19 a pusher 32 is mounted to slide longitudinally and with the trough formed concave, as shown particularly in cross-section in Fig. 4, the 25 pusher 32 is formed with a convex lower side, the complement of the concavity of the fuel trough. To move the pusher 32 longitudinally of the trough a chain 33 or other flexible means is employed extending 30 longitudinally of the said trough and passing at the lower end over a roller 34 and at the upper end over a sprocket 35 mounted upon a shaft 36 which preferably extends laterally through the side of the stoker and 35 is provided with any approved means for imparting rotary motion thereto, here shown as the crank arm 37. The chain 33 may form an endless conveyer extending entirely around the roller and sprocket, but preferably 40 a rod 37 is mounted upon the under side of the stoker with the turn buckle 38 interposed in the length of said rod and adapted to exert varying degrees of tension 45 upon the rod and chain. To permit the chain 33 to enter and leave the trough 19, 50 passages 39 and 40 are provided, the former in the lower end and the latter in the upper end, and blocks 41 and 42 are carried rigidly upon the chain 33 positioned to close the 55 said openings 39 and 40 when the pusher 32 is in normal position adjacent the top of the fuel trough and to prevent the passage of fuel and air through the said passages 39 and 40. To properly journal the shaft carrying the rollers 34, a recess 43 is formed in the lower flanges of the trough and air casings, and each of the flanges is provided with a half hole as shown at 44 in Fig. 8 and in dotted lines in Fig. 5 to permit the insertion of a bolt therethrough to prevent 60

displacement of the shaft journaled in said recess. A like recess 45 is provided in the flanges at the upper end of the members to permit the journaling therein of the shaft 36 carrying the sprockets, but as the strain 70 upon such shaft is downwardly, it is not usually found necessary to employ any means for maintaining the shaft within such recess. 75

Adjacent the lower end of the fuel trough a plate-like portion 46 is provided and an auxiliary plate 47 is positioned to span the concavity of the trough and provided with upstanding ears 48 positioned to engage the lower one of the series of twyer blocks 80 and prevent displacement thereof. The lower flanges of the sections are also provided with recesses 49 within which is mounted a shaft 50 carrying the ash or dumping grate and preferably extending 85 outwardly through the side of the stoker and provided with means for rotating, as the crank arm 51. On the shaft 50 are mounted a number of grate frames 52 carrying grate sections 52, the frames being 90 operated by shaft 50. The operating means shown in Figs. 9 and 10 include shaft 50, grate frames 52 curved at 53 to embrace the shaft, and a lever 54 secured to the curved portion by pivot 55. The grate frames 95 may be mounted directly on shaft 50 as shown at 50a. The lever 54 is provided with a detent 56 having a notch proportioned to fit and engage the squared shaft 50 and with a spring 57 adapted to hold 10 the said lever in engagement with the shaft. A hook or ring 58 is also provided at the lower end of the lever to permit a fire hook to be engaged therewith to move the lever out of engagement with the shaft. 10 The frames may be operated together by turning shaft 50, and may be moved separately by their respective levers 54.

In cases where room is limited for the addition of the fans without the line of the 11 boiler or furnace, it is preferable to connect the air blast directly to the stoker and preferably in the manner shown in Figs. 2, 3, 5 and 11. The fan can be attached to any 11 number of sections and the casing 62 is constructed separate from the stoker sections and applied to a cut out portion 63 of the flange 21.

That shaft 64 is continuous carrying any 12 number of fans desired. The fan casing 62 being open at or adjacent the center permits air to pass freely into the stoker twyer when the blast is not being operated permitting the stoker to be used under natural chimney draft at any time desired. Within 12 the casing 62 any approved form of rotary fan is employed shown conventionally at 65 which said fan is mounted upon the shaft 64 and rotated therewith in any approved manner. 130

Above the stoker a fuel hopper 61 is mounted with an opening in the lower side thereof adapted to be substantially closed by the pusher 32 when at the extreme upper limit of its movement. When the pusher 32 is moved downwardly the fuel hopper being open will permit the fuel to pass from the hopper through the opening and follow the pusher downwardly within the trough 10 but the weight of such fuel will prevent the fuel returning with the pusher and owing to its angular or inclined structure the fuel is pushed outwardly toward and into the burning fuel mass.

In operation, the troughs are filled with fuel in substantially the usual and ordinary manner; and when the fuel bed is thoroughly ignited more fuel is supplied thereto until a proper combustion bed has been secured.

Fuel is supplied to the hopper 61 and by a movement of the shaft 36 the pusher is moved downwardly, as indicated by the arrow in Fig. 1, permitting fuel to fall from the hopper downwardly. The downward movement of the pusher also moves the accumulations within the trough downwardly upon the grate 52 automatically breaking up the surface of the fuel bed. When the pusher is returned, the fuel mass is again stirred so that undue coking is prevented

and when returned to normal position the pusher causes the fuel to move toward the upper end of the combustion chamber. When sufficient ash has accumulated upon the dump grates they are dumped by rotating the shaft 50 by means of the crank arm 51. If for any reason it is desirable to dump a single section of the dump grates or plate independently the fire hook is inserted in the hook 58 of the lever 54 and the lever drawn as indicated by the arrow, which releases the detent 56 from engagement with the shaft 50 and also moves the grate 52 angularly relative thereto. The return movement of the fire hook and lever 54 returns the grate section to position until the detent 56 again engages the squared shaft 50 to hold it in normal position. Any approved construction of ash hopper or chute may be disposed beneath and to receive material from the ash grate 52, as shown in Fig. 1.

I claim:

1. In a stoker, a fuel trough disposed at an inclination and having openings formed through the opposite ends thereof, a pusher movable longitudinally within the trough, means to move the pusher, and stops carried by the moving means and arranged to close the openings.

2. In a stoker, a plurality of fuel troughs provided with upwardly extending sides, plates provided with downwardly extending flanges forming with the troughs an air cas-

ing, means for connecting the flanges of adjacent plates, and means connecting the sides to provide a fuel surface above a plurality of such casing divisions.

3. In a stoker, a fuel trough disposed at an inclination and having openings formed through opposite ends thereof, a pusher movable longitudinally within the trough, a flexible cable adapted to move the pusher and extending without the trough and through the said openings, and stoppers carried by the cable adapted to close the openings.

4. In a stoker, an inclined fuel support, a shaft journaled adjacent the lower edge of the fuel support, grate frames carried by the shaft and movable therewith upon rotation thereof and arranged to receive fuel from the said inclined fuel support, and means to permit any number of frames to remain stationary while the remaining frames are actuated.

5. In a stoker, a fuel support, a squared shaft journaled adjacent the support, a plurality of grate frames mounted upon the shaft and arranged to receive fuel from the fuel support, an operating lever mounted upon each of the frames and arranged to engage the shaft, and means to facilitate the disengagement of the lever from the shaft.

6. In a stoker, fuel troughs provided with an air casing, twyers mounted on the troughs and in communication with the air casing, means within the fuel troughs adapted to distribute fuel therein, a flexible device connected with said fuel moving means, means to operate the flexible device, independent dumping grate frames located at the lower end of the troughs, a shaft carrying and adapted to operate the frames simultaneously, and means to move the grate frames independently of each other.

7. In a stoker, a plurality of fuel troughs having upwardly extending sides, plates provided with downwardly extending flanges forming with the troughs an air casing, means for connecting the flanges of adjacent plates, means connecting the sides to provide a fuel surface, and fuel moving means within the troughs.

8. In a stoker, a plurality of fuel troughs having upwardly extending sides, means for forming an air casing beneath the troughs, means for closing the ends of the troughs, a fuel moving device within each trough, and a cable connecting the fuel moving device with the means last mentioned.

In testimony whereof I affix my signature in presence of two witnesses.

PAUL L. CROWE.
